MANUEL ENOS, OF LEMOORE, CALIFORNIA.

SPARK-PLUG.

1,119,144.

Specification of Letters Patent.

Patented Dec. 1, 1914.

Application filed November 10, 1913. Serial No. 800,212.

To all whom it may concern:

Be it known that I, MANUEL ENOS, a citizen of the United States, and a resident of the town of Lemoore, county of Kings, and State of California, have invented a new and useful Improvement in Automatic Cleaning Spark-Plugs, of which the following is a specification.

My invention relates to spark plugs and its object is to readily and automatically clean them from carbon or other foreign matter without taking them apart and without stopping the engine of which they are a part. I accomplish these and other objects by the mechanism hereinafter described.

In the drawings which accompany this specification Figure 1 is an isometric view of the spark plug complete. Fig. 2 is a sectional view of the spark plug on the line a shown in Fig. 1, and Fig. 3. Fig. 3 shows a top view of the outer casing. Fig. 4 is a view of a lock washer. Fig. 5 is a flat view of a ratchet wheel used in adjusting the plug. Fig. 6 shows the ratchet complete. Fig. 7 is a view of the spark plug from the bottom. Fig. 8 shows the inner casing.

Referring to said drawings, A is an outer shell which is threaded on the outside lower end 1. The outside upper end 2, is adapted to receive a wrench. On the inside thereof is a lateral round hole 4, which uniformly diminishes in diameter from the bottom to a shoulder 6, near the top, and from the said shoulder 6, to the top of such outer casing 35 the said hole 4, extends with a uniform diameter. At points on the extreme bottom of outer casing A, are projections j and j'. b and b' are holes through the walls of outer casing A, extending preferably downward, 40 obliquely, from the outside, above the threads 1. The top of said outer casing A has a small section i, shown in Figs. 2 and 3 cut out.

C is the core of the spark plug and consists of a casing r, shown in Fig. 8, the lower end of which is turnably fitted in the outside casing A. Casing r is hollow and has holes c and c' through its wall. In casing r and above holes c and c' is a shoulder x and from 50 shoulder x to the top of casing r the diameter of the hole is approximately uniform. Holes c and c' can register with holes b and b' by turning core C. The upper portion of casing r is threaded and laterally fluted on the outside thereof. The fluting is 55 illustrated on Fig. 1, by character 8.

e is a metal core extending through the center of the plug, having four points f, f', f², and f³ at the bottom thereof, and is threaded for a nut d at the top thereof. 60 Metal core e is insulated and is covered with porcelain or other nonconducting material 3, except at each end thereof, which is exposed. The porcelain or nonconducting material 3 is fitted snugly in the upper end of casing r 65 and has a shoulder x' thereon which fits snugly against shoulder x. There is a space 5 left between casing 2 and insulation 3 which communicates with opening c and c'. 70 s is a washer of insulating material which separates the top of inner casing r from nut d.

p is a ratchet wheel adapted to fit over the neck 9 of casing r, with the inner projections 7 following the fluting 8.

o is a projection at a point on the flat side of ratchet wheel p.

D is a lever which is adapted at one end to fit over neck 9. It has an ordinary pawl 12.

13 and 15 are ordinary followers on neck 9, having lock washer 14 between them.

In assembling my spark plug I insert the core C inside of outer shell A, with neck 9 extending beyond the top of such outer shell 85 then insert ratchet wheel p over neck 9 with projection o in the space i cut out of the top of outer shell A. The object of projection o and cut out portion i is to limit the revolution of core C, and when the 90 spark plug is assembled holes b and c, and holes b' and c' should register when the core C is turned either to the extreme right or extreme left. Lever D is inserted over neck 9 so dog 12 engages notches 18 in ratchet 95 wheel p. The purpose of ratchet wheel p and dog 12 is to permit lever D to be locked to ratchet wheel p in any one of the notches in said ratchet wheel so lever D can extend in any direction from 100 the center of ratchet wheel p from any direction from the spark plug. It will be noted that as ratchet wheel p is locked to casing r, and lever D is locked to ratchet wheel p in one of several adjustments, by 105 turning lever D casing r is turned and the ports b c and b' c' can be opened or closed. When the spark plug is adjusted for use in an engine and it is desired to clean it while the engine is running, the 110 core C is moved by lever D so the opening b registers with opening c and opening b'

registers with opening *c'* when the force of the explosion in an engine will drive a blast through openings 5 clearing the spark plug. Then the core C can be turned so openings *b* 5 and *c*, and *b'* and *c'* are not continuous, and the spark plug will not permit the escape of gas. I have formed the lower end of metal rod *e* with four projections or spark points.

If it is desired to prime the cylinders 10 when the engine is not in motion, the openings *b* and *c* can be made to communicate, and gasoline injected.

What I claim as my invention and upon what I desire Letters Patent is:

15 1. In a spark plug, the combination of an outer shell having a threaded lower portion and a conical opening with the larger diameter at the bottom of such shell, an inner casing rotatably fitted in such outer shell 20 and extending upward beyond it, an insulated metal core extending lengthwise in such inner casing and tightly fitted within the upper part thereof, an air chamber between the lower end of the wall of the inner casing and the insulation of the metal core 25 open at the bottom, holes through the walls of the inner casing and outer shell adapted to register and to form an opening from said air chamber to the outside when the inner casing is turned to a fixed point, and to have such communication cut off by rotating the inner casing in the outer shell beyond such fixed point, a handle attached to the top of such inner casing adapted to turn such inner 30 casing, all substantially as described.

2. In a spark plug, the combination of an outer shell having a threaded lower portion, an inner casing rotatably fitted in such outer shell and extending upward beyond it, an 40 insulated metal core extending lengthwise in such inner casing and tightly fitted within the upper part thereof, an air chamber between the lower end of the wall of the inner casing and the insulation of the metal core,

open at the bottom, holes through the walls 45 of the inner casing and outer shell adapted to form an opening from said air chamber to the outside when the inner casing is turned to a fixed point, and to have such communication cut off by rotating the inner casing in the outer shell beyond such fixed point, means for rotating such inner casing consisting of a track in the top of the outer shell, a lever having one end fitted over the top of the inner casing and attached thereto, and a 50 projection attached to said lever adapted to travel in said track within fixed limits, all substantially as described.

3. In a spark plug, the combination of an outer shell having a threaded lower portion, 60 an inner casing rotatably fitted in such outer shell and extending upward beyond it, an insulated metal core extending lengthwise in such inner casing and tightly fitted within the upper part thereof, an air chamber between the lower end of the wall of the inner casing and the insulation of the metal core 65 open at the bottom, holes through the walls of the inner casing and outer shell adapted to form an opening from said air chamber 70 to the outside when the inner casing is turned to a fixed point, and to have such communication cut off by rotating the inner casing in the outer shell beyond such fixed point, means for rotating such inner casing 75 consisting of a track in the top of the outer shell, a ratchet wheel locked to the upper end of the inner casing having a projection thereon adapted to travel within fixed limits in said track, a lever turnably mounted on 80 the top of such inner casing and by means of a dog adapted to be locked to such ratchet wheel, all substantially as described.

MANUEL ENOS.
